[57] CLAIM

The ornamental design for a rotatable display stand, as shown and described.

DESCRIPTION

FIG. 1 is a perspective view of a rotatable display stand showing my new design;

FIG. 2 is a side elevational view, the opposite side being a mirror image thereof;

FIG. 3 is a front elevational view, the rear being a mirror image thereof;

FIG. 4 is a top plan view thereof;

FIG. 5 is a bottom plan view thereof;

FIG. 6 is a cross-sectional view taken along line X—X of FIG. 3;

FIG. 7 is a perspective view of a second embodiment of that shown in FIG. 1;

FIG. 8 is a front elevational view, the rear being a mirror image thereof;

FIG. 9 is a side elevational view, the opposite side being a mirror image thereof;

FIG. 10 is a top plan view thereof;

FIG. 11 is a bottom plan view thereof; and,

FIG. 12 is a cross-sectional view taken along line X—X of FIG. 8.
